UNITED STATES PATENT OFFICE.

ALFRED G. RYLEY, OF CANTON, OHIO, ASSIGNOR, BY MESNE ASSIGNMENTS, TO THE McCASKEY REGISTER COMPANY, (INCORPORATED IN 1914,) OF CANTON, OHIO, A CORPORATION OF OHIO.

ACCOUNT-REGISTER.

1,143,073.

Specification of Letters Patent. Patented June 15, 1915.

Original application filed September 24, 1908, Serial No. 454,552. Divided and this application filed December 28, 1912. Serial No. 739,022.

To all whom it may concern:

Be it known that I, ALFRED G. RYLEY, a citizen of the Dominion of Canada, residing at Canton, in the county of Stark and 5 State of Ohio, have invented certain new and useful Improvements in and Relating to Account-Registers, of which the following is a specification.

This invention relates to improvements 10 in account registers, more particularly of the type in which a separate compartment, bodily removable from a casing, is provided for receiving each individual account.

This application is a division of my application Serial No. 454,552, filed September 24, 1908.

For the purpose of illustration, I have, in the accompanying drawings, shown and herein described one form of apparatus embodying my invention.

Figure 1 is a view partly in front elevation and partly in section of a register embodying my invention. Fig. 2 is a longitudinal sectional view, partly on line 2—2 and partly on line 2'—2' of Fig. 1, one of the trays being shown in section. Fig. 3 is a detail view of a bill holding tray and its guides, part of the latter being shown in section. Fig. 4 is a section on the line 5—5, Fig. 3. Fig. 5 is a top plan view of the parts illustrated in Fig. 3. Fig. 6 is an elevation of a modified form of bill tray. Fig. 7 is an end view thereof. Fig. 8 is a view of a bill tray and its guides provided with means for automatically removing it. Fig. 9 is a longitudinal section of the parts shown in Fig. 8.

In the drawings, 1 indicates a pedestal or base and 2, 3, uprights or standards rigidly secured to the base.

40 4 is a horizontally disposed shaft mounted at either end in bearings 5, 6, carried by the uprights, 2, 3, respectively. Rigidly secured to the said shaft 4 in any suitable manner near the opposite ends thereof, are 45 heads or disks 7, 8. The space between these end heads 7, 8, may be divided into any desired number of sections by means of disks or plates 9 rigidly secured to the shaft 4. The innermost pair of disks 9 are spaced a 50 suitable distance apart to receive between them a bearing standard 10 having a forwardly projecting arm 11 with upwardly

extending ears 12, 13, in which is mounted a rotatable shaft 14.

15 is a bevel pinion rigidly secured to the 55 lower end of the shaft 14 and in mesh with the bevel gear 16 rigidly secured to the shaft 4 between the partition plates 9.

The disks 7, 8, and 9 divide the space along the shaft 4 into a plurality of tray or 60 file holding sections, each section being provided with a circular series of bill holding trays or files, each designated as an entirety by 17.

The trays or files are preferably supported 65 in the sections, as clearly indicated in Fig. 2. As there shown the inner ends of the trays set out some distance from the shaft 4, about which they are located in circular series, and longitudinal central lines of the 70 ways or guides in which the trays are supported are tangential to a circle concentric with the axis of shaft, 4, but some distance out therefrom, with the result that the trays in the top of the supporting drum at any 75 time tip back from the front of the register. This causes a sort of overlapping of the successive trays of the series, the end of each being exposed from the front of the device to a greater extent than would be the case 80 were the arrangement of the trays about the shaft, 4, radial. This is of advantage as it makes it possible to expose to the eye the indexing devices that may be arranged at or carried by the trays at their outer ends. 85

The trays 17 are mounted so as to be longitudinally movable within their respective sections, and preferably bodily removable therefrom. Each tray is preferably formed of sheet metal and has a rear wall 18, a bottom wall 19, and side walls 20, 21. The metal at the upper end of the tray is cut to form an index tab or extension 22 and a forwardly extending section 23, preferably at the left hand side of the file. Each file may 95 be provided with any suitable type of bill clip or retainer. For the purpose I have shown a spring clip 24, suitably secured at its lower end to the metal of which the file is formed and carrying an indexing tab 25. 100

Each file 17 is mounted in its respective section in suitable guides. The guide for the right hand side of each tray is preferably a U-shaped piece of metal, indicated by

- 26, having a bottom section turned in at 27 to form a stop with which the bottom wall 19 of the tray engages. The guide 28 for the left hand side of the file is U-shaped in cross section only at its upper end, as indicated at 28', beneath this U-shaped section the guide being L-shaped, as indicated at 28", and at its lower end this guide 28 has an inwardly turned portion 29 to serve as a stop 5 for the left hand side of the tray corresponding to the stop 27 for the right hand side. At its upper end the front wall of the U-shaped portion 28' is bent over on itself as indicated at 28".
- 10 30 is a flat spring rigidly secured at 31 to the rear wall of the U-shaped section 28'. This spring is curved inwardly as indicated at 30^a to engage the rear wall 18 of the file and press it forward in order that the top 20 section 23 of the file at its front end may come beneath the stop 28^b so as to normally prevent the sliding of the file from the guides when the carrying disks are rotated to bring the files into inverted position.
- 15 25 A register such as described may be mounted in a suitable casing which is preferably formed of metal with which may be combined fire-proofing material for the protection of the files from fire or heat. The case 30 is of any suitable construction, that represented in the drawings comprising a main compartment, 32, into which the plurality of sets of rotatable file holders or trays and their supporting drums and the operating 35 parts thereof are placed. The top of the compartment 32 is closed by a hinged cover 34, in which is formed an opening, 35, through which the exposed ends of a line of the trays may be viewed, and through which 40 the trays may be bodily passed in placing them in the register or removing them from the casing. This opening may be closed by a sliding gate or cover, 36, which may be provided with a lock, 37, for securely closing 45 the register when not in use. The main cover, 34, for the top of the case also carries a lock, 38, for holding it closed. In front of the main compartment, 32, there may be arranged an extension of the case, 39, in which 50 are arranged a set of drawers or trays, 40. The top, 41, of this extension is preferably a frame containing a transparent glass which is arranged to overlie a support, 42, upon which may rest an index sheet carrying all 55 the names of the persons whose accounts are kept in the register with suitable designating numbers or marks set opposite each name to assist the operator in quickly exposing opposite the opening, 35, the tray 60 carrying any desired account.
- The inclined shaft, 14, extends forward and carries at its outer end a revolving pointer, 44, which is located outside the curved front portion of the compartment, 65 32, of the casing. It lies in an aperture

formed by notches in the meeting edges of the cover, 34, and the stationary portion of the upper front curved wall of the casing, so that such shaft does not interfere in any wise with the movements of the said cover. 70

Interposed between the arm or revolving pointer, 44, and the front wall of the casing is a stationary disk, 43, on the front face of which are numbers or other designating marks corresponding with those set opposite the names of the persons whose accounts are kept in the register. If it be desired to examine the account of a particular person the sheet under the glass, 41, is consulted and the number or mark set opposite the name 80 of such person is observed. The pointer is then turned to the corresponding mark on the disk, 43, whereupon the tray containing sections will be so moved as to bring the tray carrying the desired account opposite the 85 opening, 35. The arm, 44, is preferably provided with an operating knob or handle 45, which may have its spindle or shank arranged to be projected through the arm and so shaped, as indicated at 46, as to enter 90 shallow recesses formed in the plate, 43. A spring, 47, operates to set the end, 46, of the handle against the plate 43 and into the sockets or recesses formed therein, thus holding with sufficient security the arm in the 95 position to which it may be set, though permitting it to be moved from place to place at will.

In order to prevent the drum in which the bill-carrying trays are mounted from overrunning when moved, I prefer to provide a retarding or retaining device. This may be of any suitable construction. That shown comprises a plate, 48, carried by one of the disks such as 9, of the drum and formed with 100 an undulating or recessed surface against which bears a spring-held roller, suitably mounted in the standard 10.

I have already described some of the advantages incident to tangentially arranging the individual trays in the drum. The illustrated disposition of the trays not only fully exposes the index tabs or extensions, 22, as they are successively brought opposite the opening, 35, but also permits the 110 upper ends of the account slips themselves to be observed. It is therefore better to print such slips so that the totals or balances of the accounts shall appear near the upper edges of the slips, that may be readily discernible through the opening 35. Balances can thus be taken off by turning the drum to successively bring line after line of the slips opposite the said opening, without necessitating their removal or handling. 115

My invention is not limited in its useful appliances to the particular embodiment thereof thus far described and illustrated in the drawings to which reference has been made. Thus as illustrated in Figs. 6 and 130

7 a form of bill tray or carrier may be employed adapted to prevent the unauthorized handling or removal of the slips after they have once been filed. The frame of the 5 tray is in its essential features similar to that already described. It, however, is provided with a front cover or plate, 50, hinged to the tray near its lower end, at 51. The said cover is held in place, thereby closing 10 the tray, by a swinging bail, 52, so placed that it may be swung over the upper end of the tray to release the cover. This bail, 52, is adapted to be sealed in position to hold the cover closed, by one or more seals 53. 15 These are to be applied to the tray by a person authorized to use them. A broken seal would indicate that a tray has been opened by one not authorized so to do, the seal thus forming a safeguard against the handling 20 of account slips by any one not having rightful access thereto. The tray near its upper end has a transverse slit 54 through which the account slips can be passed. A spring, 55, preferably carried by the cover, 25 50, holds the slips in place within the tray. The spring is shaped to have an operating portion as indicated at 56, which extends out through a slot 57 in the cover 50, so that the spring may be raised within the 30 tray whenever it is desired to pass a slip into the latter. In this form of slip holder or tray it is best to use an account slip where the balances or totals are set down near the lower edge thereof, and I therefore provide an aperture 60, in the cover plate 50, through which the balances or 35 totals may be seen and it is evident that either the bail 52 or the edge of the slit 54, at the upper end of the front cover 40 or plate 50 of the tray, may serve as a wall to be engaged by the stop 28^b carried by the support for normally holding the tray therein.

The trays or bill holders thus far described are adapted to be removed from their holder manually. It is sometimes desirable that they should be automatically removable, or at least partially so. In Figs. 8 and 9 I have illustrated means for automatically lifting the trays and projecting them to a greater or less degree from their supports and guides in the drum. The tray 17 is supported in the guides, 26, 28, which may be of the form already described, it being essential that there be a stop for the upper end of the tray to normally hold it in its guides. 58 designates a spring arranged to bear against the lower end of the tray and tending to force it upward against 50 said stop or out of the supporting guides. A convenient way of mounting the spring is indicated in Fig. 8 where it is represented as being supported at the lower end of one of the guides, 28. A person using the 55 register can easily release a tray from the

stop 28^b by pressing its upper end out of engagement with the stop when the spring 58 will force it upward. The force of the spring is usually sufficient to project the tray about one-half way out of its supporting guides. Instead of using the holding stop 28^b a locking spring 58' arranged to engage with the upper edge of the tray or bill file may be employed. This as represented in Fig. 9, can conveniently be secured to one side flange of the guide 28 and have its end rest behind a keeper, 59. 70 To those skilled in the art of making account registers of the class described, many alterations in construction and widely differing embodiments and applications of my invention will suggest themselves, without departing from the spirit and scope thereof. My disclosures and the description herein 75 are purely illustrative, and are not intended 80 to be in any sense limiting.

What I claim is:

1. In an account register, a tray for holding individual account slips having a cover for closing the tray, and arranged to be sealed to the tray by a sealing device when the cover is closed, the tray having an entrance slit through which the slips may be passed when the cover is sealed. 90

2. In an account register, a tray for holding individual account slips having a cover for closing the tray, and a bail adapted to engage with the free end of the cover for holding it closed, the tray having an entrance slit through which the slips may be 100 passed when the cover is closed.

3. In an account register, a tray for holding individual account slips, having a cover for closing the tray, and a spring within the tray for confining the slips, the spring 105 extending through an opening in the tray and being operable from the outside when the tray is closed, and the tray being provided with an entrance slit.

4. In an account register a tray for holding individual account slips, having a cover for closing the tray, a bail adapted to engage with the end of the cover for holding it closed, and arranged to be sealed by a sealing device, and a spring within the tray 110 for holding the slips in place. 115

5. In an account register, a tray for holding individual account slips, a cover for closing the tray, means for holding the tray cover closed, the said tray being formed with an entrance slip through which the slips may be passed when the cover is closed, and a spring carried by the cover for confining the slips in the tray. 120

6. In an account register, a tray for holding individual account slips, a cover for closing the tray, means for holding the tray cover closed, the said tray being formed with an entrance slip through which the slips may be passed when the cover is closed, 125 130

and a spring carried by the cover for confining the slips in the tray, the said cover being formed with an opening through which the spring extends, whereby it may be operated from outside the tray.

7. In an account register, the combination of an individual account slip holding tray adapted to slidably engage with a support, the said tray having a back and a bottom, 10 a spring normally bearing against said back

to hold account slips in position thereon; and a wall arranged at the upper end of the tray and adapted to engage a stop carried by the support.

In testimony whereof I affix my signature, 15
in the presence of two witnesses.

ALFRED G. RYLEY.
